UNITED STATES PATENT OFFICE

GEORGE E. SHELDON, OF PHILIPSBURG, PENNSYLVANIA

COMPOSING-STICK ATTACHMENT

Application filed December 20, 1927, Serial No. 241,299. Renewed April 29, 1929.

This invention relates to improvements in composing sticks, and more particularly to devices for attachment thereto whereby the stick may be held in tilted position during 5 composing.

Devices of this type have heretofore been proposed, but it is a special virtue of the present invention that the support may be moved out of its position so that the composing stick 10 may be moved downward into parallelism with a suitable base.

One of the objects of the present invention is, therefore, to provide a composing stick having a device to support it in an inclined 15 position, this device being operable to permit the stick to move downward into a horizontal position on a composing stone or galley.

Another object of this invention is to provide such a holding device in the form of an 20 attachment for the usual composing stick, so that the parts may be cheaply and readily manufactured and attached to the stick.

A further object of the invention is to provide a composing stick attachment comprising 25 a body portion to be attached to the stock and a support portion pivotally mounted on the body portion, said devices being frictionally engaged with each other to maintain respective positions.

30 Still another object of the invention is to provide a composing stick attachment of two portions frictionally engaged with each other, one of said portions having a device disposed in the path of movement of the other portion 35 to limit the movement of the latter under the weight of the type in the composing stick, but being adapted to move out of such position so that the stick may be moved downward into horizontal position on a galley or composing 40 stone.

With these and other objects in view, as will appear in the course of the following specification and claims, one form of execution of the invention has been illustrated upon 45 the accompanying drawings, in which:

Figure 1 is a perspective view of an attachment applied to a composing stick, with the stick supported in an inclined position.

Fig. 2 is an end view of the attachment, 50 showing in full lines the parts in the inclined

position, and in dotted lines the parts in the collapsed position.

Fig. 3 is a sectional view on line 3—3 of Fig. 2.

In the illustrative form shown on the drawing, the composing stick is comprised, as usual, of the base 10 having the end wall 11 and rear wall 12, and a movable partition 13. The attachment of this illustrative form comprises a body portion 14 having the inwardly 55 bent upper and lower flanges 15, 16, to engage the end wall 11 of the composing stick, and thereby retain the attachment thereon. An end lug 17 engages the wall 12 of the stick 60 and determines the position of the attachment 65 thereon.

The supporting portion 18 is of sheet metal similar to the body portion 14, and is pivotally mounted thereon by a rivet 19 so that the parts may have a rocking movement with 70 respect to each other. The supporting portion 18 is provided with a thumb member 20 so that the portions may be manually moved to any desired position with respect to each other. The upper corner 21 of the body portion 18 which remains opposite the body portion 14 is bent inward to maintain a frictional engagement therewith, so that the two portions remain frictionally in adjusted position. A tongue 22 is stamped out of the metal 75 of the body portion 14 and projects toward the supporting portion 18 and into the path of the latter so that at a predetermined angular position of the two portions with respect to each other, the upper edge of the supporting 80 portion 18 comes against this lug, and thereby the portions are prevented from making any further movement under the weight of the 85 type and the composing stick itself. This position has been illustrated in the drawings 90 as being substantially of 45°, but it will be understood that any other angle may be employed instead without departing from the scope of this invention.

In operation, the attachment is slid onto the 95 end of the composing stick, and the compositor pushes the thumb piece 20 downward until it forms an angle of substantially 45°, as noted above, and is then held both by the frictional resistance to movement of the corner 100

21 and by the tongue 22. The composing stick may now be placed upon a flat bed or even upon the partitions of the type case, and the individual types placed in it, spaced and leaded as customary. When the stick is full, it may be brought upon the composing stone or into the galley, and the operator, while retaining the type in position by the usual end slug or lead, can push downward upon the stick itself to overcome the frictional resistance of the corner 21 and of the tongue 22, so that the portions 14 and 18 collapse or close with respect to each other, wherewith floor 10 of the composing stick is brought to a horizontal position with respect to the stone or galley, so that the type composition may be slid out of the stick onto the stone without the liability of forming pi, as would be the case if the body of type had to be lifted through the air.

20 When the composition has thus been removed, the stick may be prepared for similar use again by merely pushing downward on the thumb piece. It is further apparent that the attachment may be collapsed and the stick used in the hand without removal of the attachment, which is light and without encumbrance upon the stick itself.

25 It is apparent that the invention is not limited to the form of execution shown, but that it may be employed in many ways within the scope of the appended claims.

What I claim as new and desire to secure by Letters Patent is:

30 1. A composing stick attachment comprising a body portion adapted to be attached to the composing stick, said body portion having a tongue projecting out of its plane, and a support portion pivoted to said body portion, said support portion having a part thereof bent out of plane to establish a frictional relationship with said body portion to maintain the portions at a given position with respect to each other so that said portions may hold the stick in an inclined position, the upper edge of said support portion being adapted to engage said tongue to prevent a further closing pivotal movement of said portions with respect to each other under the 35 weight of the type in said stick.

2. A composing stick attachment comprising a body portion adapted to be attached to the composing stick, a support portion pivoted to said body portion so that said portions may be closed onto one another and the stick brought flat upon a base by pressing it downward thereupon, said body portion having a member projecting into the path of movement of said support portion to limit said closing 40 movement so that said portions may hold the stick in an inclined position, said member being movable into and out of such limiting position.

3. A composing stick comprising a type holder and a supporting portion pivoted to

be rocked with regard thereto, means to frictionally limit the rocking movement of said supporting portion so that the type holder may be held in an inclined position with respect to a base upon which said supporting portion rests, said means being withdrawable from limitation of said movement by an increased pressure upon said type-holder.

4. A composing stick comprising a type holder and a supporting portion pivoted to be rocked with regard thereto, means to limit the rocking movement of said supporting portion so that the type holder may be held in an inclined position with respect to a base upon which said supporting portion rests, said means being withdrawable from limitation of such movement so that said type holder may be rocked directly downward onto said support.

In testimony whereof, I affix my signature.

GEO. E. SHELDON.
